OIL CLEANER

Graham G. Somers, Flint, Mich., assignor to
 C. V. S. Manufacturing Company, Flint, Mich.,
 a corporation of Michigan

Application June 20, 1933, Serial No. 676,705

8 Claims. (Cl. 210—57)

This invention relates to improvements in oil cleaning devices and pertains particularly to a device which is designed primarily for use upon motor vehicles for cleaning the lubricating oil thereof.

5 The primary object of the present invention is to provide an efficient oil cleaner which is designed for use in place of the present oil filter or strainer which is commonly employed on motor vehicles.

10 Another object of the invention is to provide an oil cleaning device which operates through centrifugal action to separate heavy particles from lubricating or other oil and includes a sedimentation chamber in which the particles are deposited.

15 A still further object of the invention is to provide an oil cleaner which is divided into two sections, into one of which oil is discharged in a manner to constantly keep it in a whirling condition, while in the other part the oil is static and the particles separated by centrifugal action, settle by gravity therein.

20 Still another object of the invention is to provide an oil cleaner which will make use of the settlement by gravity of impurities in the oil when the oil is not being circulated therethrough, to trap such impurities and prevent their returning into circulation.

25 The invention will be best understood from a consideration of the following detailed description taken in connection with the accompanying drawing forming part of this specification; with the understanding, however, that the invention is not confined to any strict conformity with the showing of the drawing but may be changed or modified so long as such changes or modifications mark no material departure from the salient features of the invention as expressed in the appended claims.

30 In the drawing:—

Figure 1 is a vertical sectional view through the device embodying the present invention;

35 Figure 2 is a horizontal section taken substantially upon the line 2—2 of Figure 1;

40 Figure 3 is a view in side elevation of the circulating vein at the outlet opening, the supporting collar therefor being in section;

Figure 4 is a view in plan, on a reduced scale, 45 of the device.

50 Referring now more particularly to the drawing wherein like numerals of reference indicate corresponding parts throughout the several views, the numeral 1 indicates a receptacle which is preferably of circular cross section and having

the closed bottom 2. The wall of the receptacle at the top is turned outwardly to form the flange 3 and a cover 4 is removably placed over the open top of the receptacle and overlies the flange 3 in the manner illustrated.

55 For the purpose of mounting the receptacle 1 in upright position upon a suitable support there is provided the bracket 5 which is provided with the right angled portion 6 which has a central aperture 7 formed therethrough which is of a diameter corresponding to the diameter of the receptacle 1. Around the opening or aperture 7 an annular series of bolt-holes 8 is formed for the reception of bolts 9. The head 4 of the device positions against the under side of the horizontal portion 6 of the supporting bracket and is provided with a plurality of apertures which align with corresponding apertures in the flange 3 and which are also aligned with the holes 8 so that the bolts 9 may pass downwardly therethrough to engage in 70 threaded apertures in a ring 10 which surrounds the receptacle 1 and bears against the under side of the flange 3. A suitable gasket 11 is interposed between the flange 3 and the head 4 to prevent leakage.

75 The central part of the head 4 is provided with the outwardly pressed off-set 12 which is centrally apertured and a second outwardly pressed off-set is formed at 13 adjacent the side of the head. This second off-set portion is also centrally apertured. Extending through the aperture in the portion 12 is an internally threaded nipple 14 which is flanged for contact with the top of the head and which receives upon its inner end the retaining ring 15 which is suitably secured thereto.

80 Surrounding the retaining ring 15 is a collar 16 which has an inturned portion which is held by the collar against the head 4 and secured in this collar is a radially slotted disk 17 which has the portions between the slots turned slightly to form 85 blades, the purpose of which will be hereinafter more fully set forth.

85 Extending through the opening in the off-set portion 13 is an interiorly threaded inlet nipple 18, the outer end of which is suitably shouldered 100 to engage the top of the head while the inner end receives a retaining ring 19, against the inner face of which is secured a disk 20 which is pressed to form the channel 21 which extends radially from the center of the disk to the edge thereof. 105 This channel 21 is directed tangentially of the receptacle wall so that oil injected therewith through the nipple 18 will be discharged against the wall in such a manner as to create a whirling movement in the body of oil with which the re- 110

ceptacle is filled. The blades of the circulating vein 17 are so inclined that they have their lower edges directed against the movement of the oil in the receptacle as it is caused to move through its 5 forcible injection through the channel 21 so that the whirling movement of the oil will be increased by the blades picking up the same in such a manner as to offer the least resistance to the oil movement and also in a manner to direct it to and 10 through the outlet nipple 14.

Substantially centrally of the receptacle 1 there is disposed the inverted frusto-conical plate 22, the center of which is provided with an opening 23 and as the overall diameter of the plate is less 15 than the interior diameter of the receptacle an opening 24 is formed around the edge thereof.

Beneath the plate 22 and concentric with the receptacle, is a cylinder 25 and disposed vertically in the area between this cylinder and the wall of 20 the receptacle is a plurality of baffle plates each of which is indicated by the numeral 26 and each of which extends from the bottom 2 of the receptacle to the under side of the plate.

Disposed beneath the plate 22 and in spaced 25 relation therewith, is the flat annulus 27 which has its outer edge in contact with the wall of the receptacle. This annulus is set in suitable slots in the baffles and lies directly beneath the opening 24.

30 Within the cylinder 25 is a plurality of baffle walls 28 each of which extends from the wall of the cylinder 25 inwardly and joins with the other at the common center.

In operation, the inlet oil pipe is connected 35 with the nipple 18 while the outlet is connected with the nipple 14 and the oil or other fluid enters the upper part of the receptacle above the plate 22 tangentially through the action of the channel 21. The receptacle 1 is filled with the fluid to be 40 cleaned and the entering oil therefore sets up a circulatory movement of the portion of the fluid lying above the plate 22. As this movement of the fluid is against the lower edges of the blades of the circulating vein 17, as previously described, 45 these blades will increase the whirling movement of the fluid and assist in carrying the fluid off through the outlet 14 without hindering the motion of the body as a whole.

Due to the plate 22 and the baffle walls 26 and 50 28 therebeneath, the fluid below the plate 22 will remain stationary and any heavy sediment in the upper fluid will be worked toward the wall of the receptacle and will move downwardly through the opening 24 into the lower outer chamber of 55 which the baffle walls 26 form a part. The other lighter sediment will collect in the eddy formed at the center of the moving body of fluid and gradually settle onto the plate 22 passing therethrough by way of the opening 23 and into the quiescent fluid within the cylinder 25. The baffle walls 28 in this cylinder also prevent any undue motion of the liquid therein and thus give the entering sediment an opportunity to settle by gravity.

60 From the foregoing it will be readily apparent that a device of the character herein set forth will efficiently operate to remove sediment from oils or other fluids, wherein the removal of such sediment is desirable, and since no filters or strainers are employed the device will operate efficiently 65 over a long period of time without attention.

Having thus described the invention, what is claimed is:—

1. A fluid cleaner, comprising a receptacle having an inlet and an outlet opening at the top

thereof, said inlet opening being disposed adjacent the wall of the receptacle, a plate disposed across the receptacle and dividing the same into an upper and a lower portion, there being a central passage through the plate and a peripheral passage thereabout from the upper to the lower portions, means in the lower portion of the receptacle for preventing the movement of liquid therein, and means in the upper part of the receptacle for establishing a whirling motion of the liquid therein as other liquid is injected through the inlet opening.

2. A fluid cleaner, comprising a receptacle having an inlet and an outlet opening at the top thereof, said inlet opening being disposed adjacent the wall of the receptacle, a plate disposed across the receptacle and dividing the same into an upper and a lower portion, there being a passage from the upper to the lower portions, means in the lower portion of the receptacle for preventing the movement of liquid therein, means in the upper part of the receptacle for establishing a whirling motion of the liquid therein as other liquid is injected through the inlet opening, and means adjacent the outlet opening for facilitating the flow of liquid from the receptacle without interfering with the whirling motion thereof.

3. A liquid cleaner, comprising a receptacle, a plate disposed across the center of the receptacle and dividing the same into an upper and a lower portion, there being a passage centrally through said plate and a passage past the plate adjacent the wall of the receptacle, baffle walls disposed vertically in the lower portion of the receptacle between the bottom thereof and said plate, said walls extending radially to prevent whirling movement of liquid therein, and means in the upper part of the receptacle for directing inflowing liquid tangentially to establish a whirling of the liquid in the upper part of the receptacle.

4. A liquid cleaner, comprising a receptacle having a top provided with inlet and outlet openings, a plate within the receptacle dividing the latter into an upper and a lower portion, there being a passage from one of said portions to the other, means in the upper part of the receptacle for directing the inflowing liquid tangentially of the circular receptacle wall to create a whirling movement of the liquid in the upper portion of the receptacle, baffle walls disposed in the lower portion of the receptacle to prevent motion of the liquid therein, and a bladed body disposed over the outlet of the receptacle for facilitating the flow of fluid therefrom without affecting the whirling movement of the same.

5. A liquid cleaner, comprising a circular receptacle, a plate disposed in the receptacle and dividing the same into an upper and a lower portion, an inlet and an outlet opening in the top of the receptacle, channel forming means overlying the inlet opening for directing the incoming fluid tangentially in the receptacle to set up a whirling movement of the fluid in the upper portion thereof, a body overlying the outlet opening of the receptacle and comprising a plurality of radial blades inclined to present their lower edges to the whirling fluid, and vertical radially directed baffle walls in the lower part of the receptacle between the bottom thereof and said plate.

6. A liquid cleaner, comprising a circular receptacle, a plate disposed in the receptacle and dividing the same into an upper and a lower portion, an inlet and an outlet opening in the top of the receptacle, channel forming means overlying the inlet opening for directing the incoming fluid

5 tangentially in the receptacle to set up a whirling movement of the fluid in the upper portion thereof, a body overlying the outlet opening of the receptacle and comprising a plurality of radial blades inclined to present their lower edges to the whirling fluid, said plate having a central opening and having a passage between its edge and the wall of the receptacle, a cylinder disposed vertically in the lower part of the receptacle between the bottom thereof and said plate, and baffle walls within the cylinder and within the area between the cylinder and the receptacle wall and extending from the bottom of the receptacle to the plate and disposed radially of the receptacle.

10 7. A liquid cleaner, comprising a circular receptacle, a plate disposed in the receptacle and dividing the same into an upper and a lower portion, an inlet and an outlet opening in the top of the receptacle, channel forming means overlying the inlet opening for directing the incoming fluid tangentially in the receptacle to set up a whirling movement of the fluid in the upper portion thereof, a body overlying the outlet opening of the receptacle and comprising a plurality of radial blades inclined to present their lower edges to the whirling fluid, said plate having a central

opening and having a passage between its edge and the wall of the receptacle, a cylinder disposed vertically in the lower part of the receptacle between the bottom thereof and said plate, and baffle walls within the cylinder and within the area between the cylinder and the receptacle wall and extending from the bottom of the receptacle to the plate and disposed radially of the receptacle, and a flat annulus disposed beneath the said plate and having its outer edge contacting the receptacle wall and terminating at its inner edge short of said cylinder.

15 8. A fluid cleaning device, comprising a receptacle, inlet means at the top of the receptacle arranged to inject fluid in a manner to set up a whirling motion, an outlet for the receptacle, means dividing the receptacle into upper and lower chambers, a plurality of division elements disposed in the lower chamber radially thereof, and means permitting the passage of matter separated from the injected liquid from the upper chamber into the lower chamber adjacent the wall of the receptacle and at the central part of the said receptacle dividing means.
